UNITED STATES PATENT OFFICE.

JOHN H. GRIFFIN AND JAMES S. GRIFFIN, OF HARVARD, ILLINOIS.

IMPROVEMENT IN MACHINES FOR GRINDING CUTTER-BARS FOR HARVESTERS.

Specification forming part of Letters Patent No. 123,890, dated February 20, 1872.

To all whom it may concern:

Be it known that we, JOHN H. GRIFFIN and JAMES S. GRIFFIN, of Harvard, in the county of McHenry and State of Illinois, have invented a new and valuable Improvement in Machines for Grinding Mower and Reaper Teeth; and we do hereby declare that the following is a full, clear, and exact description of the construction and operation of the same, reference being had to the annexed drawing making a part of this specification, and to the letters and figures of reference marked thereon.

Figure 1 of the drawing is a representation of a rear view of the body of the horse. Fig. 2 is a top view of the grinding apparatus, showing the method of applying and grinding.

This invention has relation to means for facilitating the grinding of reaper-guards; and it consists in the construction and novel arrangement of the horse, hereinafter described.

In the accompanying drawing, the letter A designates the frame of the grinding-machine; B, the emery-wheel. C represents the body of the horse, having a longitudinal slot formed in it, passing through from its upper to its under side, as indicated at d. E E represent the legs of the horse. These legs are spread at the feet and mounted upon casters z, in order

that its movement may be free in any direction. F represents a pivot-bolt, by means of which the reaper-bar G is secured upon the body C of the horse, in such a manner that a free motion of rotation is permitted about the pivotal point, or, if desired, the bar may be secured rigidly in position upon the body C by tightening the nut h. I represents a cross-bar, through which the pivot-bolt F passes. This cross-bar serves as a bearing for the nut h.

This grinding-horse is designed to serve a purpose of great convenience. The heavy finger-bar, weighing from two hundred to three hundred pounds, can, by its aid, be easily managed and the cutting-edges of the teeth brought in contact with the grinding-wheel or removed therefrom with great facility.

We claim as our invention—

The grinding-horse herein described, consisting of the slotted body C, bolt F, casters z, and cross-bar I, substantially.

In testimony that we claim the above we have hereunto subscribed our names in the presence of two witnesses.

JAMES S. GRIFFIN.
JOHN HART GRIFFIN.
